FOLDING BERTH AND SEATING UNIT

Warren J. Williams, Richmond Hill, N. Y.

Application March 24, 1950, Serial No. 151,558

4 Claims. (Cl. 5-9)

1

This invention relates to folding berths and, more particularly, to the duplex type adapted, when not in use, to be swung into a recess in a bulkhead or partition wall, and particularly adapted to ship staterooms or other sleeping quarters (and also to railway sleeping cars and similar installations). The invention is shown in connection with ship sleeping quarters which, when not used for sleeping, is used as a lounge or parlour, and for this purpose, has a seat or sofa.

One of the objects of this invention is to provide a duplex folding berth in which the upper berth may be turned more than 90° to an inclined or slanted position in which it can be readily made-up by a person standing on the floor (i. e., without having to climb up to make the bed). An allied object is to provide means enabling the upper berth to be selectively turned 90° to sleeping position, or a greater angle (such as 115°) to said make-up position.

Another object of invention is to provide a safety lock or latch arrangement which will assure that the berth will remain positively in selected position, whether that be the normal, closed position, or the open, sleeping position, or the aforementioned make-up (slanted) position.

A further object of invention is to provide in the folding berth of the type described, an equalizing spring which will make easier the task of returning the berth to closed position. An allied object is to provide an equalizing spring for a folding berth which is readily adjusted to regulate the tension of the spring, as may be required.

A still further object of invention is to provide the folding berth with an improved form of berth-ladder which has a number of features which will be fully described and pointed out in the ensuing specification.

For the attainment of the foregoing and such other objects of invention as may appear or be pointed out herein, I have shown a preferred embodiment of my invention in the accompanying drawings, wherein:

Fig. 1 is a front view of the improved folding berth in non-sleeping position, closed except for the sofa or seat;

Fig. 2 is likewise a front view but showing the upper berth in open or sleeping position;

Fig. 3 is a front view similar to Fig. 2, but showing both the lower and the upper berths in open, sleeping position, and with the berth-ladder extended to the floor;

Fig. 4 is a side view of the improved folding berth, with the upper berth in open or sleeping position;

2

Fig. 5 is an elevational section taken on the line 5-5 of Fig. 2, and showing the upper berth in closed position and the lower berth in open or sleeping position;

Fig. 6 is a horizontal cross-section through the improved folding berth;

Fig. 7 is a fragmentary sectional elevation taken substantially on the line 7-7 of Fig. 2, showing the upper berth in make-up position;

Fig. 8 is a fragmentary section, in elevation, taken on the line 8-8 of Fig. 6, showing particularly, the equalizing spring;

Fig. 9 is a section taken longitudinally through the improved berth on the line 9-9 of Fig. 6;

Fig. 10 is a fragmentary front view of the front of the upper berth (in open or sleeping position), showing the berth-ladder in reposed position;

Fig. 11 is a front view of the berth-ladder in its operative position;

Fig. 12 is an enlarged detail of the ladder articulation, taken on the line 12-12 of Fig. 11;

Fig. 13 is an enlarged detail of the ladder construction taken on the line 13-13 of Fig. 10; and

Fig. 14 is a sectional view taken on the line 14-14 of Fig. 11, showing further details of the ladder construction.

Referring first to Fig. 6, it will be seen that the improved folding berth of this invention is disposed between a pair of stanchions 10, 10, which extend normally from bulkhead 1. Referring now to Figs. 4 and 5, it will be seen that the upper berth 20 is pivotally mounted (between said pair of stanchions 10, 10) to turn on axis 21 from the open or sleeping position (shown in Fig. 4) to the closed position (shown in Fig. 5); it will also be seen that the lower berth 30 is similarly pivotally mounted to turn on axis 31 from its closed position (shown in Fig. 4) to the open or sleeping position (shown in Fig. 5). The

structure of the two berths, e. g. that of the upper berth, is best shown in Figs. 7 and 6, from which it will be seen that the berth (the upper berth, that is) has a floor panel 22 (Fig. 7), constructed of hollow plate construction and end walls 23, 23 (Fig. 6).

The bottom face of floor panel 22 presents a smooth, uninterrupted surface or plane 24, which is decoratively treated because when the berth (upper) is closed—as it is in Fig. 1—said decorated or finished surface 24 will be exposed, as shown in said figure.

To open the upper berth from its closed position (shown in Fig. 1), a hand-latch 25 is provided, Fig. 1, at one side. A similar hand-latch 35 is provided for the lower berth. Stops are provided to limit the extent of opening of the berths

to open position; the stops associated with the lower berth 30 will be first described, because these are simple, fixed stops (unlike those of the upper berth, subsequently explained). Referring to Fig. 4, a lug or stop 36 projects laterally—on both sides—from floor panel 32 of the lower berth 30, which, when the berth is turned 90° to open position (see Fig. 5) abuts and is stopped by a lug or stop 16 provided in the side stanchion 10, or rather, stanchions 10, 10.

Similar fixed stops are not provided in connection with the upper berth, because of the feature of the improved berth of this invention which enables the upper berth to be turned more than 90°, to an inclined or slanted position in which it can be readily made-up by a person standing on the floor. Upper berth 20 is shown in Fig. 7 in said inclined make-up position. That is, whereas in sleeping position, upper berth 20 is turned 90° (to position of Fig. 4), in the make-up position, it is turned 115°, Fig. 7. I have found this angle of slant to be satisfactory, but it is to be understood that my invention is not limited to this, or any other angle.

To enable the upper berth 20 to be selectively turned 90° to sleeping position or 115° to make-up position, the stops on the berth (unlike 36, 36) are not fixed but are adjusted selectively. For this purpose, a shaft 27, see Fig. 9, extends across the length of the upper berth 20, being mounted in end walls 23 for an extent of turning, and is provided at both ends with an arm or stop-arm 26, 26. Shaft 27 is turnable (by means subsequently described) from a position in which it is normal to the floor plate 24 of the berth 20 (as in Figs. 5 and 4) to a position in which it abuts or lies against the floor plate 24 (as in Fig. 7). Shaft 27 is journaled in the walls 23 to rotate about a constant axis. The ends of shaft 27 are fixed to stop lugs 26, 26 so that stop lugs 26, 26 may be turned to lie against floor plate 24 by turning the shaft 27. When the end stop lugs 26, 26 are in said normal position (Figs. 5-4), they contact, when the upper berth is turned 90° (as in Fig. 4), a predetermined surface 15, 15 of stops 14, 14 fixed in the side stanchions 10, 10 see Figs. 4, 5 and also Fig. 9. Referring particularly to Fig. 4, the stop surface 15 is so disposed that, with the end stops 26, 26 in said normal position (of Figs. 5-4), these stops 26—15 will engage to limit the open turning to 90° as in Fig. 4. But if shaft 27 had been turned to lie end stops 26, 26 against floor plate 24 (as in Fig. 7), stop surface 15 will not be effective to limit the turning to said 90°. Instead, the berth will continue turning—to 115°, as explained above—until the side, rather than the end, of stop 26 abuts a second (inclined) stop surface 13 provided on stop lugs 14, 14.

To enable shaft 27 to be turned to selective position, its end stops 26, 26 as just described, it is provided with a centrally-disposed bevel gear 28, Fig. 9, and the plate 24—see Fig. 1—is provided with a small aperture 29, wherethrough may be inserted a hand-tool 9 which has a bevel gear 8 at its inserted end. After inserting tool 9 to mesh its gear 8 with bevel gear 28, it is turned to impart a turning in the desired direction, to shaft 27.

It had been mentioned earlier that the berth may be opened and closed by manipulation of hand-latches 25 (upper berth) and 35 (lower berth), Fig. 1. These will now be described with reference to Figs. 4, 5 and 7, and also Fig. 6. Se-

cured on the two side trunions 11, 11, Figs. 6-7, upon which upper berth 20 is pivotally mounted (to turn on axis 21, 21 as before described) are two stationary discs 17, 17, see especially Figs. 5-4-7. As there shown, the periphery of disc (i. e., discs) 17 is provided with a plurality of notches in which may be received a lug 48 provided at the distal end of a lever 47 pivotally mounted, at 46, to the end wall 23 of the upper berth. At said distal end of lever 47 but on the side opposite said lug 48, is articulated one end of a link 45, the other end of which is articulated to one arm of a bell-crank lever 44, pivotally mounted at 43. To the other arm of the bell-crank lever 44 is articulated one end of the hand latch 25. A tensile spring 42, anchored at one end to end wall 23 and secured at its other end to link 45.

By reason of tensile spring 42, lever 51 is constantly urged towards the periphery of stationary disc 17, so that its said lug 48 will enter certain notches provided in the periphery of disc 17. One of such notches is designated 18c and is located, see Fig. 5, so that, when upper berth 20 is in closed position, lug 48 will snap into said notch 18c, to positively lock the parts in closed position, as shown.

To manipulate the safety lock (for opening the berth), hand-latch 25 is pulled out, to the left in Fig. 5, thus turning bell-crank lever 44 counter-clockwise and raising lever 47, thus withdrawing its lug 48 from notch 18c. Upper berth 20 is then turned 90° until stopped by 26—15 (as described above); in this position of the berth, lug 48 snaps into a second notch 18 on the periphery of disc 17 as shown in Fig. 4. A third notch 18m is provided in the periphery of disc 17, into which, lug 48 snaps, when the upper berth is in slanted or make-up position, as in Fig. 7.

A similar safety lock arrangement is provided on lower berth 30 and manipulated by hand-latch 35, Fig. 1, the parts being the same reference numerals as described and shown with reference to the upper berth. The only difference is that the disc 17 associated with the lower berth has only two notches, viz., 18c and 18, there being no notch for a slanted or make-up position.

Referring to Fig. 2, flashing 12 is provided to the rear of the berths, between the side stanchions 10, 10. The berths, such as upper berth 20, Fig. 2, are provided with rollers 19 which engage said flashing 12.

Referring to Fig. 7, the sides of the berth are provided with rubber bumpers 37, 37 which contact rubber bumpers 38, 38 which line the opening in the housing, see Fig. 1.

An equalizing coil spring 2, Fig. 8, is provided at each truncheon or axis 21, see Fig. 6. As clearly shown in Fig. 8, the inner end of the coil spring is held in a stud or spindle (axis) 21 of upper berth 20, while the other end of the spring is secured to stanchion. This securement is made adjustable so that the proper tension may be applied to the coil spring. For this purpose, a plate 50, Fig. 8, is held to stanchion 10, as by means of threaded bolt 51, and provided with an opening or hook 52 by which the end of the spring can be secured. By turning bolt 51, the spring anchor 50 may be moved towards, or away from, the right side of stanchion 10, thus varying the tension of coil spring 2.

The berth-ladder in its normal (not-in-use) position, is turned so that it is reposed horizontally along the front of the upper berth 20, as clearly shown in Fig. 2. To enable it to be so turned,

its two sidepieces 60, 70 are pivotally secured to the front of the berth. The details of construction are clearly shown in Figs. 10-11, from which it will be seen that one of the sidepieces, more particularly, 60, is radially aligned with the pivotal point 61 of securing to the berth, whereas the other sidepiece 70 is offset or spaced from its pivotal point 71. That is, sidepiece 70 is connected to the pivotal securing by an elbow fitting 72.

The sidepieces 60, 70 may be made tubular and round (cylindrical) but for several reasons, such as strength, beauty of appearance, economy, etc. they are given the oval shape shown in Fig. 13 and hollowed internally by a large central bore 63, 73 and two smaller bores 64, 74. The manner of articulating the sidepieces to the front of the berths, represented by plate 20^x in Fig. 12, is shown in that figure with reference to the sidepiece 60. In the central bore 63 at the upper end of sidepiece 60 is securely held the threaded, bolt-like end 65 of a fitting 66. Freely rotatable on bolt end 65 and disposed between the end of sidepiece 60 and a pair of lock nuts 67 is a disc or roller 68. Fitting 66 has a spherical seat 69 for a ball or sphere 59 which projects from a bracket 57 secured to the aforesaid plate 20^x of the upper berth. Also secured to the bracket is a cam surface 58 engaged by the disc roller 68. The other sidepiece 70, Figs. 10-11, is similarly articulated, the parts being similarly designated 58-68-66.

By reason of the spherical connection 59-66 between the two sidepieces 60, 70 and the upper berth and the provision of cam surfaces 58, 58 and rollers 68, 68, the ladder, more particularly, its sidepieces 60, 70 is extended outwardly away from the wall, when the ladder is being turned to open position, see Fig. 3.

The rungs of the ladder, designated 53, are disposed between sidepieces 60, 70, being articulated at 54, 54 to elbows or lateral projections 55, 56 directed inwardly from sidepieces 60, 70.

The berth-ladder is held in its folded, non-use position by means of a latch 75, Fig. 13, which is turnably mounted to a bracket 79 secured to the berth, as by the pin 76. Pin 76 may not only turn relative to the bracket 79, but may also be pulled outwardly, together with latch 75, away from the bracket. However, a small compression spring 77 abutting the headed end 78 of the pin, normally maintains the latch 75 in close relation to bracket 79, as shown in Fig. 13, in which position the sidepieces 60, 70 are clamped in position, as shown in Fig. 13. Preparatory to turning the ladder to operative position, the latch 75 is pulled away from bracket 79 (i. e. to the right in Fig. 13), the opening 75^x enabling the hand to grasp the latch. The latch is then turned 90° to the position shown in Fig. 3, thus freeing the sidepieces of the ladder.

Upper berth 30 is provided with a protective railing at the head end, i. e., at the right as viewed in Fig. 3. Said protective railing comprises an ell-shaped tube having one leg 80 extending longitudinally, Fig. 3, and its other leg 81 extending transversely, Fig. 4. When the upper berth is turned to closed position, said protective railing is collapsed for folded and becomes erected to protecting position, when the berth is turned

to sleeping position, as in Fig. 4. For this reason protective rail 81 (80) is mounted on the berth by a parallel linkage which comprises a pair of supporting arms 82, 83, pivotally mounted on the 5 end wall of the upper berth at 84 and 85 respectively, said arms being distally articulated to the ends of rail 81, Fig. 4. To one of said arms, more particularly, 82, is articulated one end of the "anchorage" link 86, the other end of which is 10 pivotally mounted to the berth wall at 87.

I claim:

1. In a berth installation disposed adjacent a bulkhead, in combination, a pair of stanchions secured to the bulkhead at the spaced distance 15 of the berth, at least one berth disposed between the bulkheads, axially-aligned trunnions for pivotally mounting the berth, a stationary disc disposed on one of said trunnions at one of said stanchions, a lever pivotally mounted at one end 20 wall of the berth having a distal lug engaging the periphery of the disc, said disc periphery having a plurality of notches, spring means for normally urging said lever towards the disc to engage its said lug in said notches, one of said notches being angularly disposed on the disc to lock the berth in closed position, and another of said notches being disposed 90° from said first notch to lock the berth in open sleeping position, manual means for withdrawing said lever lug, said berth adapted to be turned more than 90° from its closed position to an inclined slanted make-up position, said stationary disc having a peripheral notch to lock said berth in said slanted make-up position, a coil tensile spring disposed at said trunnion, one end of the spring being secured to said trunnion to turn with the berth, the other end of the spring being secured to said stanchion.

2. The combination according to claim 1 wherein in the inner end of the coil spring is secured to the trunnion and the outer end thereof is secured to the stanchion.

3. The combination according to claim 2 wherein said spring securement to the stanchion is adjustable.

4. The combination according to claim 3 wherein in said adjustable spring securement comprises a block having a hooked opening for receiving said outer end of the coil spring, and a threaded bolt for regulatably securing the block to the stanchion.

WARREN J. WILLIAMS.
